(Continued)(**) Term: **15 Years**(21) Appl. No.: **29/609,963**

Primary Examiner — Jennifer Rivard

Assistant Examiner — Alison M Ofstun

(22) Filed: **Jul. 7, 2017**

(74) Attorney, Agent, or Firm — Seager, Tufte & Wickhem LLP

(51) LOC (12) Cl. **28-03****CLAIM**(52) **U.S. Cl.**

The ornamental design for a ball joint compact, as shown and described.

USPC **D28/82****DESCRIPTION**(58) **Field of Classification Search**

FIG. 1 is a perspective view of the ball joint compact showing the new design;

USPC D28/64.1, 76-84; D9/503-505, 722, 529, D9/420, 425, 428; D3/295; D19/103, D19/106
CPC A45D 33/006; A45D 33/003; A45D 33/04-33; A45D 33/025; A45D 33/02; A45D 33/20; A45D 33/22; A45D 33/24; A45D 33/26; A45D 33/28; A45D 33/18; A45D 40/22; A45D 40/222; A45D 40/24; A45D 2200/051-053; A45D 2040/223-228

FIG. 2 is a front view thereof;

See application file for complete search history.

FIG. 3 is a rear view thereof;

FIG. 4 is a right side view thereof, the left side being a mirror image;

FIG. 5 is a top view thereof;

FIG. 6 is a bottom view thereof;

FIG. 7 is a perspective view thereof, with the lid open;

FIG. 8 is a right side view thereof, with the lid open, the left side being a mirror image;

FIG. 9 is a rear view thereof, with the lid open;

FIG. 10 is a perspective view thereof, with the lid open and partially tilted; and,

FIG. 11 is a top view thereof, with the lid open and partially tilted.

The broken lines in the drawings illustrate unclaimed portions of the article which form no part of the claimed design. The claimed design extends to the broken line boundaries but does not include the boundaries or the area within the boundaries.
